UNITED STATES PATENT OFFICE

FRANKLIN H. MILLER AND WILLIAM M. SHOFFNER, OF DAYTON, OHIO

ALL STEEL HOT AIR FURNACE

Application filed May 25, 1931. Serial No. 539,776.

This invention relates to improvements in furnaces, and has for its object to provide an improved, all steel hot air furnace.

It is particularly the object of this invention to provide an all steel hot air furnace in which there is an external case within which is located a heating chamber or drum, which has therein a removable grate member.

10 It is also an object of this invention to provide, in connection with an air furnace, means to admit air into the furnace above the grate so that a current of air and gases may be maintained without causing an undue and unnecessary combustion of the fuel in the furnace and on the grate.

It is particularly the object of this invention to provide, in connection with a hot air furnace, a case which has therein a combustion chamber which forms with the case an air chamber, and means connected with the combustion chamber for providing a gas passageway for heating the air in the air chamber as it rises. This gas passageway is formed so that it will offer the least resistance to the rising air in the air chamber, and form the greatest amount of contacting surface for the air whereby it may be more readily and completely heated.

20 30 These and other advantages will appear from the following description taken in connection with the drawings.

Referring to the drawings:

Figure 1 is a front elevation of the furnace with part of the front wall removed.

Figure 2 is a vertical section through the furnace showing the relative positions of the case and the combustion chamber located within the case and the air chamber between the case and the combustion chamber.

40 Figure 3 is a section on the line 3—3 of Figure 1.

Figure 4 is a section on the line 4—4 of Figure 3.

45 Figure 5 is a view similar to Figure 2 showing the upper end of the case, with the heating flue in reverse position to that shown in Figure 2.

50 Figure 6 is a view showing in detail the removable grate unit.

The furnace is more or less rectangular in shape, and has a front wall 1, side walls 2, a back 3, a bottom 4 and a top 5, all composed of sheet metal and so united that there is an all steel case forming the outer walls of an air chamber and supports for a combustion chamber and grates.

55 The top is inclined inwardly toward the center so that it is in the shape of an inverted trough, which tends to direct the rising air in the chamber toward the outlets for the hot air in the upper end of the chamber. These outlets are indicated by the numeral 7 and may be any number. In Figures 1 and 2 the outlets are shown. In order to supply fresh air there are provided inlets 6 at the lower or bottom end of the case. The inlets and outlets may be used for the recirculation of air from the room, through the case and back into the room, or they may be used for taking fresh air from the outside into the case and distributing it into the room through the outlets.

60 70 75 With the exception of the outlets and inlets and an opening 8 for the admission of fuel and removal of ashes and for the purpose of draft, the case is of one continuous solid piece of sheet steel. In the opening 8 the front part 9 of the fire box and drum is located. This fire box and drum is composed of sheet steel and is welded to the other parts of the case. It is substantially rectangular in shape and has a rear wall 10 and side walls 11. The rear wall slopes upwardly and toward the front, as indicated by the numeral 12, and passes into a downwardly inclined part 13 of the front wall of the fire box and drum. This construction of the fire box is well illustrated in Figure 2.

80 85 90 95 100 At the extreme upper curved end of the fire box and drum are two outlet openings 14, which serve as draft holes and communicate with flues, later to be described. Around the front of the fire box and drum is a frame 15 suitably attached to the front wall 9 by means of rivets, bolts or other suitable means. This frame has three openings therein. The lower opening, next to the bottom of the case, is closed by an ash door 16, in which there is a draft door 17. This door opens to a part of

the fire box immediately below the grates and is for the purpose of removing ashes from this part of the fire box.

Immediately above the opening closed by 5 the door 16 is a fire door 18 for the purpose of putting fuel into the fire box for combustion purposes. Immediately above the fire door is an air inlet door 19. Each of the 10 doors 18 and 19 has a slide therein. On the door 18 this slide is indicated by the numeral 20, while on the door 19 this slide is indicated by the numeral 21. These slides are for the purpose of admitting air into the drum part 15 of the fire box, or that part of the fire box above the combustion chamber.

The openings or outlets 14 pass into arms 22 of a U-shaped heating flue supported around the upper end of the fire box and drum. The open ends of this U-shaped 20 heater project through the front wall of the case, as indicated in Figure 1, and are closed by doors 23. These doors are for the purpose of enabling the removal of ashes and cinders and other solid material that collect in the 25 heating flue.

In the arm of the heating flue adjacent an 30 opening 14 is an inlet opening 24 in line with the opening 14. Between the sides of the fire box and drum and the adjacent sides of the arms of the heating flue is a pipe 25, which 35 has on each end a flange 26. This pipe fits around the holes 14 and 24 with the flange against the walls. Opposite the pipe and attached to each of the walls 11 and the inside 40 wall of each arm of the heating flue is a ring 27. These rings are fastened to the flanges 26 by means of rivets or any other suitable means. The relative positions of the parts are shown in Figure 3.

45 The hot air and gases rise from the combustion or fuel chamber, pass into the upper part of the combustion chamber or drum, and out through the openings 14 into the arms 22 of the heating flue. The closed end of the U-shaped heating flue is enlarged, as indicated by the numeral 28, and has extending outwardly therefrom an outlet opening 29 which leads into a stack or flue by which the draft is produced. Adjacent the outlet 29 is a trap 50 30, closed by means of a door 31. The purpose of this trap is to catch ashes, cinders and other solid material that may be carried along with the gases and the hot air passing from the combustion chamber.

55 The U-shaped heating flue may be arranged in a reverse position to that shown in Figure 2 and in the position shown in Figure 5. As shown in Figure 5, the trap 30a extends upwardly and may project 60 through the wall of the case adjacent the heating flue, or a pipe 30b may be attached to this trap and extend across the upper end of the case and out through the front wall thereof, above the doors. In either event, the smoke stack or smoke flue is attached to

the outlet end of the trap 30a. When the trap 30a is used for forming part of the draft channel the opening 29a is used for cleaning purposes and may be closed by a door similar to that shown in Figure 2 and indicated by the numeral 31.

In order that the U-shaped heating flue may be easily reversed it is symmetrical in every respect, the inlet opening 24 in one arm being located similarly to the opening 75 in the other arm. This U-shaped heating flue is made of sheet steel, and is connected to the case by being welded thereto.

When the heating flue is in the position shown in Figure 5 and there is a pipe 30b connected to the trap 30a which extends across the top of the case but within the case, there is an increased amount of heating surface over which the air passes before leaving the air inlets, thereby increasing the 80 heating effect of the furnace. By arranging the heating flue in the position shown in Figure 5 not only is the heating area increased but means is provided for attaching the outlet flue in another position so that 85 the furnace may be more readily and satisfactorily adjusted with relation to the parts of the room or basement in which it is located.

90 Figure 6 shows a plan view of a removable grate unit adapted to be used with the furnace described herein. This grate unit may be placed in and removed from the fire box through the fuel door. For supporting the grate unit the fire box has suitable ledges 100 for seating the frame 32a of the grate. This frame is flat and rectangular in shape having vertical grate supporting flanges 32.

95 The grate is a removable grate and has side flanges 32, suitably supported on the inside of the combustion chamber so that they may be readily removed from and placed in the proper position within the combustion chamber. These lateral flanges are used to support transversely arranged 110 grate members 33, each of which has on each end a trunnion 34 which fits in a notch 35 in the upper edge of one of the side flanges 32.

115 Each grate has extending downwardly therefrom an arm 36, and attached to the lower end of each arm is a link 37 which extends out through the front of the furnace. The outer end of this link has attached thereto the lower end of a lever 38, pivoted intermediate its ends at a point 39 so that by 120 operating the lever the grates may be rocked on their trunnions.

125 As shown in Figure 2 the grates are in a horizontal position, but by operating the lever 38 these grates may be tilted so that ashes, clinkers and the like accumulated thereon may be dumped in the ash chamber beneath the grates. Associated with the fire box and on each side of the grates is a protecting wall 40 to protect against the excessive heat due 130

to the immediate vicinity of the burning fuel. There is also provided at the upper edge of the fuel admission door a ledge 41, which tends to divert the rising gases and heat from the door above the fuel admission door.

Whenever the furnace is in operation and a great amount of circulation of gases is desired without increasing the amount of fuel burned, the slide door in the door 19 may be opened so that air is admitted into the upper part of the drum or combustion chamber. This air coming in through this door contacts with the rising gases from the fuel and becomes thoroughly mixed with these gases, due to the restricted nature of the opening through which the gases and air pass.

Not only is there an added quantity of gas for circulation and heating purposes without an increase in the combustion of fuel, but if any unconsumed or unburned gases may be rising from the fuel on the grates this gas, on account of the excessive heat, will take the oxygen from the air and be consumed, thereby creating a greater amount of heat without increasing the amount of fuel burned.

It frequently happens when an insufficient amount of air is admitted to burning fuel that carbon monoxide is produced, and unless burned will pass into the air without being consumed, but if the proper amount of air is added at the proper time and place this gas will be converted into carbon dioxide, thereby increasing the amount of heat without increasing the amount of fuel consumed. The taking in of the air is due to injector effect due to the rising gases in the combustion chamber or drum.

We desire to comprehend within our invention such modifications as may be embraced within our claims and the scope of our invention.

Having thus fully described our invention, what we claim as new and desire to secure by Letters Patent, is:

1. In a furnace, an integral sheet steel case having air inlets and air outlets, an integral sheet steel fire box and drum in said case forming therewith an air chamber, the side walls of the drum being vertical and the front and rear walls of said drum converging to form the top of the drum, and a heat flue in said air chamber connected to opposite sides of the drum adjacent the top thereof.

2. In a furnace, an integral sheet steel case having air inlets and outlets, a heating chamber in said case forming with the case an air chamber, said heating chamber having vertical side walls and upwardly and inwardly inclined front and rear walls forming a curved top, a U-shaped heating flue in said case with its arms on opposite sides of and connected

to the heating chamber adjacent the top and supported by the walls of the case, a cleaning door in each arm outside of the case, and an outlet from said heating flue through the back wall of the case.

70

3. In a furnace, an integral sheet metal case having air inlets and air outlets, an integral sheet steel fire box and drum in said case forming therewith an air chamber, the side walls of the drum being vertical and the front and rear walls thereof converging to form the top of the drum, a heat flue in said air chamber connected to opposite sides of the drum adjacent the top thereof, said flue having an outlet through the back of the case and a trap connected to the flue adjacent the outlet and extending through the back of the case.

75

4. In a furnace, an integral sheet metal case having air inlets and air outlets, an integral sheet steel fire box and drum in said case forming therewith an air chamber, the side walls of the drum being vertical and the front and rear walls thereof converging to form the top of the drum, a U-shaped heat flue in the air chamber having its arms connected to opposite sides of the drum adjacent the top thereof, said flue having an outlet through the back of the case, and a trap extending from the flue through the back beneath the flue.

80

5. In a furnace, a sheet metal case having air inlets and air outlets, a sheet metal fire box and drum in said case forming therewith an air chamber, the side walls of the drum being vertical and the front and rear walls thereof converging to form the top of the drum, a heat flue in said air chamber connected to opposite sides of the drum adjacent the top thereof, said flue having a clean-out opening extending through the back of the case, and a draft pipe connected at one end to the flue above the clean-out opening and having its other end extending through the front wall of the case.

90

6. In a furnace, a sheet metal case having air inlets and air outlets, a sheet metal fire box and drum in said case forming therewith an air chamber, the side walls of said drum being vertical and the front and rear walls thereof converging to form the top of the drum, a U-shaped heat flue in said air chamber having its arms connected to opposite sides of the drum and extending through the front wall of the case, a cleaning door in each arm, and a draft pipe connected at one end to the rear end of the U-shaped flue and extending through the front wall of the case.

95

In testimony whereof, we affix our signatures.
